UNITED STATES PATENT OFFICE.

ALFRED COPELLI AND FRANK ALBI, OF SPOKANE, WASHINGTON.

REGISTER FOR FIREARMS.

1,397,313.

Specification of Letters Patent. Patented Nov. 15, 1921.

Application filed April 26, 1917. Serial No. 164,776.

To all whom it may concern:

Be it known that we, ALFRED COPELLI and FRANK ALBI, citizens of the United States and resident of Spokane, in the county of 5 Spokane and State of Washington, have invented certain new and useful Improvements in Registers for Firearms, of which the following is a specification.

This invention relates to new and useful 10 improvements in registers adapted to be applied to firearms, and the primary object of the invention is to provide a register carried by the firearm, and adapted to designate the number of shots fired by the same, the 15 attachment being especially useful to keepers of shooting galleries, whereby the number of shots fired may be kept account of.

Another object of the invention is to provide a register of this character which is 20 easily applied to a firearm, and which is automatically operated by the action of the hammer, each time the firearm is discharged, to designate the number of times the same is fired.

25 Still another object of the invention is to provide a device of this character which is easily and simply constructed, inexpensive to manufacture, and one which will be very efficient in operation.

30 With these and numerous other objects in view our invention consists of the novel features of construction, combination and arrangement of parts which will be herein referred to and more particularly pointed out 35 in the specification and claims.

In the accompanying drawings:

Figure 1 is a side elevation of a rifle with our new and improved register applied thereto, showing the sight opening, through 40 the side of the breech, with which the numbers on the register are adapted to align.

Fig. 2 is a detailed side elevational view of the application of the invention to a rifle, the cover-plate being removed therefrom, 45 and

Fig. 3 is a detailed perspective view of the operating parts for connection between the register and hammer, the said parts being shown separated.

50 In describing our invention we shall refer to the drawing in which similar reference characters designate like and corresponding parts throughout the several views. In the accompanying drawing the register is 55 shown applied to a rifle, but it is obvious that the same is applicable to any type of

firearm, for instance to a revolver, by reducing the size of the parts accordingly and applying the same thereto.

The rifle is provided with the usual type 60 of stock 1, breech 2, hammer 3, and barrel and adjacent parts 4. Our registering attachment is applied to one side of the breech 2, and the same when in position is covered by a plate 5 having a sight opening 6 therein as clearly shown in Fig. 1 of the drawing.

In Fig. 2 of the drawing we have shown the cover-plate 5 removed from the breech, so as to show the interior mechanism for operating the register. The register proper 70 comprises a rotatably mounted disk 7 having a plurality of numbers 8 on its outer side adjacent its peripheral edge, the peripheral edge of said disk being formed with a plurality of ratchet teeth 9. The disk is also 75 provided with a continuous, circular slot 8^a which receives a pin 8^b secured in the stock of the gun so that the disk plate will return to its zero position when released by the locking pawl subsequently to be referred to. 80

A coiled spring 10 is associated with the axle of the rotatably mounted register disk, said spring normally tending to return the disk to starting position, that is, allowing the 0 to register with the sight opening 6 85 through the plate 5. To lock the register disk 7 there is provided a spring-pressed locking pawl 11 adapted to engage the ratchet teeth adjacent the outer end of the breech, said pawl having a shank 12 with a 90 head 13 that projects from the same and is exposed through the breech adjacent the barrel, and is movable against the tension of a spring 14 to release the locking pawl from the teeth, so as to allow the coiled spring to 95 return the ratchet disk to normal position. This locking pawl however is normally held into engagement with the register disk, to hold the same against the tension of the spring, and prevent its rotation in the direction which the spring tends to move the same. The pawl 11 is supported for rocking movement upon a pivot 14' to allow engagement of the pawl with the teeth in their successive order and a disengagement of said 100 pawl therefrom.

The operating mechanism of the register, that is, the connection between said register and the hammer 3 comprises a pair of pivoted levers 15 and 16, the said lever 15 being actuated by the hammer 3, while connected to the lever 16 is a striker 17 which has one 110

end offset as shown at 19 adapted for engagement with the lever 15. The lever 15 is provided with a pair of oppositely turned lateral projections 20 and 21, the projection 5 20 being adapted to engage the projection 19 of the striker 17, while the projection 21 is disposed normally in the path of movement of the hammer 3, so that the latter will move the striker 17 and the lever 16 for a purpose 10 presently described.

Pivottally connected with the lower end of the lever 16 is an operating pawl 22 that has its outer end adapted for engagement with the ratchet teeth 9 on the edge of the 15 register disk. This pawl is acted upon by a spring 23 which tends to raise the said pawl and to move the same rearwardly, so that it will be properly positioned for successive engagement with the teeth on the 20 disk 7 on repeated releasing of the hammer 3 of the firearm. When the firearm is discharged the hammer will act upon the lever 15 which through the striker 17 moves the lever 16 and the pawl 22 advances to shift 25 the register disk 7 the distance of a single tooth and this action is repeated every time the firearm is fired by the releasing of the hammer 3 thereof. On cocking the hammer 3 spring 23 becomes active to move the 30 pawl 22 rearwardly and upwardly to a position to engage another tooth for the advancements of the disk, thus it is seen that the latter is successively rotated in a step by step manner. It is obvious that all of 35 these parts are mounted in a countersunk portion in the side of the breech 2, and when in position the cover-plate 5 is positioned thereover to protect the operating mechanism from dirt or dust, and also render the 40 firearm much neater and more attractive in appearance. The only visible evidence of the register is through the sight opening 6 in the cover-plate that the numbers on the register plate are adapted to successively 45 align with. When the hammer is moved back, the spring 23 will move the pawl 22 from engagement with the ratchet teeth, and the upward displacement of the pawl will be limited by the stop 24 thereon engaging the 50 lever 16 or the shoulder α upon the latter to position said pawl relative to the next tooth on the disk for the further advancement thereof.

In operation when the firearm is discharged by pulling the trigger and releasing the hammer 3, the said hammer will be projected forward, and will engage the projection 21, moving the lever 15 forwardly, said movement being transmitted through 55 the link 17, and lever 16 to the pawl 22, hence driving the same forward against the spring 23, and into engagement with the ratchet teeth 9 on the register disk. This 60 will move the register disk one step, against the tension of the coiled spring 10, and will 65

cause the next number on the side of the disk to come into alignment with the sight opening 6.

When it is desired to return the register to normal position, that is to allow the 0 to 70 register with the sight opening, the locking pawl 11 is released by moving the head 13 thereof, whereupon the register disk 7 will be rotated by the spring 10. It is obvious that upon each forward step of the 75 register the same will be taken against the tension of the coiled spring 10, so that upon releasing said disk, the same will speedily 80 revolve to normal position.

This type of register for fire arms affords 80 a simple and efficient device, that is especially applicable for use on firearms used in shooting galleries, or the like, wherein the number of shots fired may be kept track of accurately. The device may be applied to 85 either a rifle or revolver as desired, and when positioned on the firearm is not visible, as the same is applied to the side of the breech, and is covered by the plate 5, thereby 90 not disturbing the general outline of the fire-arm, or making the attachment cumbersome or troublesome during the operation of said 95 firearm.

It will be noted that the register is provided with a prolonged space between the 95 teeth for the numeral 15, and 0 so that after fifteen shots have been recorded, the device will be prevented from operating, and it will be necessary to release the pawl, to allow the register to return to normal position before 100 the same will once again operate. This space prevents the operating pawl from turning the register continuously against the spring 10, after one revolution has been made, hence preventing any possibility of 105 the spring being broken.

From the foregoing description of the construction and operation of our new and improved register for firearms, the manner of applying the same to use and the operation thereof will be readily understood, and it will be seen that we have provided a simple and efficient means for carrying out the 110 objects of the invention.

Having fully described our invention, 115 what we claim as new, and desire to secure by Letters Patent, is:

1. A shot register for fire arms comprising a rotatable registering disk having peripheral ratchet teeth, a pivoted lever provided with an arm extending into the path of movement of the hammer of the arm to be actuated thereby in its falling movement, a disk actuating pawl carried by said lever, a spring acting on said pawl to retract it and move it into position to engage a succeeding tooth of the registering disk, and a retaining pawl for said disk. 120

2. A shot register for fire arms comprising a rotatable registering disk having pe- 125

ripheral ratchet teeth, a pivoted lever provided with an arm extending into the path of movement of the hammer of the arm to be actuated thereby, a disk actuating pawl carried by said lever, a spring acting on said pawl to retract it and move it into position to engage a succeeding tooth of the register- ing disk, and a spring actuated pawl to engage and hold said disk to prevent backward movement. In testimony whereof we affix our signatures hereto.

ALFRED COPELLI.
FRANK ALBI.
